US00D817238S

(12) **United States Design Patent**
Lock et al.

(10) **Patent No.:** **US D817,238 S**
(45) **Date of Patent:** **** May 8, 2018**

(54) **REARVIEW DEVICE**

(71) Applicant: **Gentex Corporation**, Zeeland, MI (US)

(72) Inventors: **Nigel T. Lock**, Holland, MI (US);
Mark R. Roth, Grand Rapids, MI (US)

(73) Assignee: **GENTEX CORPORATION**, Zeeland,
MI (US)

(**) Term: **15 Years**

(21) Appl. No.: **29/562,862**

(22) Filed: **Apr. 29, 2016**

(51) **LOC (11) Cl.** **12-16**

(52) **U.S. Cl.**

USPC **D12/187**

(57) **CLAIM**

We claim the ornamental design for a rearview device, as
shown and described.

DESCRIPTION

FIG. 1 is a front perspective view of a rearview device of the
present disclosure;

FIG. 2 is a rear perspective view of the rearview device of
FIG. 1;

FIG. 3 is a front elevational view of the rearview device of
FIG. 1;

FIG. 4 is a rear elevational view of the rearview device of
FIG. 1;

FIG. 5 is a first side view of the rearview device of FIG. 1;
FIG. 6 is a second side view of the rearview device of FIG.
1;

FIG. 7 is a top plan view of the rearview device of FIG. 1;
and,

FIG. 8 is a bottom plan view of the rearview device of FIG.
1.

The broken lines are included for the purpose of illustrating
unclaimed portions of the article and form no part of the
claimed design.

1 Claim, 4 Drawing Sheets
